UNITED STATES PATENT OFFICE.

GEORGE W. NÜTZ, OF CHICAGO, ILLINOIS.

RADIATOR.

No. 892,761.

Specification of Letters Patent.

Patented July 7, 1908.

Application filed September 16, 1907. Serial No. 892,973.

To all whom it may concern:

Be it known that I, GEORGE W. NÜTZ, a citizen of the United States of America, and a resident of Chicago, in the county of Cook 5 and State of Illinois, have invented certain new and useful Improvements in Radiators, of which the following is a specification.

This invention relates to radiators or coolers used more especially in connection with 10 the water cooled explosion engines of automobiles and the like; and the present improvement has for its object to provide a simple and economical structural arrangement and combination of parts adapted to 15 afford a maximum amount of effective cooling surface in a very compact manner, all as will hereinafter more fully appear.

In the accompanying drawings:—Figure 1. 20 is a front elevation of a radiator embodying the present improvements. Fig. 2 is an enlarged vertical section on line $x-x$ Fig. 1. Fig. 3 is a horizontal section on line $x'-x'$ Fig. 1. Fig. 4 is an enlarged detail section on line x^2-x^2 Fig. 2.

25 Similar numerals of reference indicate like parts in the different views.

Referring to the drawings, 1 and 2 represent upper and lower horizontal members, and 3 and 4 vertical side members, which are 30 connected together to form a substantially rectangular water containing casing, the center of which is open and contains a series of vertical radiation tubes 5 connected at top and bottom to the respective upper and 35 lower members 1 and 2 of the casing. Such construction is common to radiators used in connection with the water cooled engines of automobiles and the like.

In connection with the construction of 40 radiators above set forth, the material part of the present invention involves a construction and arrangement of parts as follows:—

45 6 are a series of vertical tubes arranged within the radiation tubes 5 aforesaid. Such tubes 6 are secured at their lower ends to the bottom plate of the lower section 4, and at their upper ends to an intermediate plate 7 of the upper section 1, with their respective ends open to the atmosphere to permit a circulation of air through their interior.

50 In the preferred form of the present invention and as shown in the drawings, the intermediate plate 7 constitutes a portion of a curved throat formed in the upper section 1, 55 the other portion of said throat being formed by a curved plate 8. In the forward move-

ment of an automobile or the like, such throat is adapted to deflect a current of air down through the series of tubes 6, to aid materially in the cooling action of the apparatus. 60 A marked advantage of the present construction being that the water to be cooled is in the form of a thin annular stratum inclosed between said tubes with both inclosing surfaces adapted for atmospheric radiation. 65

9 are one or more horizontal plates arranged intermediate of the upper and lower members 1 and 2 of the casing and adapted to stiffen and hold the series of tubes 5 in place. 70

10 are side brackets by which the radiator is attached to the frame of an automobile or the like.

11 is the filling neck of the radiator, closed by a suitable cap. 75

Having thus fully described my said invention what I claim as new and desire to secure by Letters Patent, is:—

1. In a radiator of the type herein described, the combination of a casing comprising upper and lower horizontal members and vertical side members forming an open center, a series of radiator tubes arranged in said center and a series of secondary tubes arranged within the radiator tubes and open 80 to the atmosphere at both ends, one of the casing members having a curved inlet throat formed by a flat plate to which the secondary tubes are attached at one end and a curved plate forming a deflector for directing the air into the secondary tubes, substantially as set forth.

2. In a radiator of the type herein described, the combination of a casing comprising upper and lower horizontal members and vertical side members forming an open center, a series of vertical radiator tubes arranged in said center, and a series of secondary tubes arranged within the radiator tubes and open 85 to the atmosphere at both ends, the upper 90 casing member having a curved inlet throat formed by a flat plate to which the secondary tubes are attached at their upper ends and a curved plate forming a deflector for directing the air into the secondary tubes, substantially as set forth. 105

Signed at Chicago, Illinois this 13th day of September 1907.

GEO. W. NÜTZ.
